ABSTRACT

A tape end detection device for a tape recorder comprising a substantial switch means to open or close alternately in cooperation with a rotary body during running of a tape, a capacitor charging and discharging through the switch means, and a detection output means actuating when after the tape stops its running and the switch means stops its opening or closing, the capacitor discharges a predetermined amount.

TAPE END DETECTION DEVICE FOR TAPE RECORDER

BACKGROUND OF THE INVENTION

This invention relates to a tape end detection device for a tape recorder, and more particularly to a device for automatically detecting the end of a running tape which has been unwound from a tape reel.

The tape end detection devices of conventional type have included one which may detect the termination of unwinding of a tape from a supply reel by detecting a sensing tape adhered adjacent to the end of the tape with a sensor. There has been another conventional detection device which may detect the termination of unwinding of a tape by reproducing detection signals previously recorded on an edge of the tape.

Such conventional detection devices specifically need the use of a special tape prearrangedly adhered with a sensing tape or having a detection signal recorded thereon. Otherwise, it is almost impossible for preferred tapes to be detected of their ends. Further, when troubles should occur in the course of running such as cutoff in the tape, the end of the cutoff tape can not readily be detected by the sensor. The latter device which cooperates with the detection signals has another disadvantage in that when the tape is rapidly supplied or it is rewound at a speed greater than the speed of ordinary recording and reproducing, a detection signal is reproduced at a frequency different from that produced in the ordinary running so that the detection of termination of the tape is not feasible.

The general object of the present invention is to remove the above described disadvantages.

SUMMARY OF THE INVENTION

A primary object of the present invention is to provide a novel tape end detection device which can securely and accurately detect on a preferred tape the termination of running of a tape after being unwound from a tape reel of a tape recorder, wherein a preferred tape can be used without the adhered sensing tape or the recorded detection signals.

Another object of the invention is to provide a tape end detection device which is capable of detecting the end of a tape irrespective of the tape speed or the end of a tape accidentally cutoff in the course of its running.

A further object of the invention is to provide a tape end detection device which has a switching circuit utilizing the rotation of the tape reel unwinding a tape and is adapted to operate the tape recorder automatically either in the stopping or rewinding modes of operation at the instant when the rotation of the tape reel has been stopped.

BRIEF DESCRIPTION OF THE DRAWINGS

Other objects and features of the invention will become apparent from the progress of the following description when read with reference to the accompanying drawings, in which:

FIG. 1 is a vertical sectional view of an embodiment of a tape reel rotation detecting part according to the invention;

FIG. 2 is a perspective view of the tape reel rotation detecting part as seen from the lower side;

FIG. 3 is an electrical circuit diagram of an embodiment of the device according to the invention; and

FIG. 4 is a time chart illustrating an operation of the device of the present invention.

DETAILED DESCRIPTION OF THE INVENTION

FIGS. 1 and 2 show an embodiment of the tape reel rotation detecting part in use for the device of the present invention. A reel shaft 11 rotatable together with a reel disk 10 is rotatably carried by a sleeve bearing 14 rigidly held between a chassis base 12 and a subchassis base 13. At the lower end of the shaft 11 is secured a cylinder 15 of an electrically insulating material. The peripheral surface of the cylinder 15 is provided with a conductor 16 consisting of a conductive material having a middle annular portion 16b and protrusions 16a and 16c respectively are provided laterally on each side of the middle annular portion and are in the same peripheral plane, with all these forming components a commutator 21. The protrusions 16a and 16c of the conductor 16 are in alternate arrangement with each other in the transverse direction. Widths of the protrusions are respectively smaller than the spaces between the protrusions.

Three brushes 17, 18 and 19 are vertically held in successive arrangement by means of a brush holder 20 secured at the lower surface of the subchassis base 13. The brushes 17, 18 and 19 are respectively electrically connected as later described and their tips are capable of being in contact with the protrusion 16a, the annular portion 16b and the protrusion 16c, respectively.

FIG. 3 illustrates an embodiment of an electrical circuit included in the device of the present invention. Switches S₁, S₂ and S₃ are formed with the brushes 17, 18 and 19. By rotation of the commutator 21, the brushes 17 and 19 alternately contact with the protrusions 16a, 16c and the insulating cylinder 15 respectively, causing the switches S₁ and S₃ alternately to open or close. The brush 18 contacts the annular portion 16b at all times during rotation of the commutator 21 so that the switch S₂ is always closed. With the described configuration of the protrusions 16a and 16c, the brushes 17 and 19 will not simultaneously contact the protrusions 16a and 16c. Therefore, the switches S₁ and S₃ will not simultaneously close but alternately open or close with a short interval of simultaneous opening. The switch S₁ is connected to a junction point of resistors R₁ and R₂, the switch S₂ to a positive side of a capacitor C₁ and the switch S₃ to a positive side of a capacitor C₂, respectively.

A resistor R₃ is connected to a contact 31a of a switch S₄ which is connected to a power source terminal 30. Base of a transistor X₁ is connected to a junction point of the resistor R₃ and the capacitor C₂. Base of a transistor X₂ is connected to a collector of the transistor X₁ and further connected to the power source terminal 30 through a resistor R₄. There is provided a relay L₁ between the collector of the transistor X₂ and the power source terminal 30. On operating, the relay L₁ changes over a switch S₅ from a contact 32a to a contact 32b. A plunger L₂ is provided in connection between contacts 31b and 32b of the switches S₄ and S₅ so as to change the operating mode of the tape recorder when it is actuated.

Operation of the described circuit is now illustrated with reference to the time chart of FIG. 4. Before starting of operation of the tape recorder, the power source terminal 30 is connected to the power source. At the instant the switch S_4 is connected to the contact 31a, the capacitor C_2 is charged approximately in three seconds through the switch S_4 and the resistor R_3 . When the terminal voltage of the capacitor C_2 rises higher than the voltage V_{BE} between the base of the transistor X_1 and the emitter of the transistor X_1 , the transistor X_1 is in a conductive state. By conductance of the transistor X_1 , the voltage drop of the resistor R_4 or the voltage V_{CE} between the collector and the emitter of the transistor X_1 falls below the voltage V_{BE} between the base and the emitter of the transistor X_2 so that the transistor X_2 becomes nonconductive.

In the operation of the tape recorder, the play mode button of the tape recorder may be pushed and the switch S_4 associated with the button may be changed over to make a connection with the contact 31b. At the instant, the transistor X_2 is in non-conductive state, the relay L_1 is not in operation and the switch S_5 is connected to the contact 32a. Therefore, the plunger L_2 will not actuate even though the switch S_4 is connected to the contact 31b.

The capacitor C_2 is then cutoff the supply of a voltage through the resistor R_3 by the change-over of the switch S_4 and starts its discharging through the base and the emitter of the transistor X_1 . The starting point of discharging is shown by a numeral 40 in FIG. 4. When the tape recorder starts operation and the tape runs, the reel shaft 11 rotates together with the supply reel to unwind the tape resulting in the rotation of the commutator 21. By rotation of the commutator 21, the switch S_1 will repeat the opening and closing operations intermittently. The capacitor C_1 is charged by a voltage divided by the resistors R_1 and R_2 at the instant the switch S_1 is ON (closed).

After the switch S_3 is turned ON after the switch S_1 being turned OFF, the electric charge in the capacitor C_1 flows to the capacitor C_2 through the switch S_3 and the capacitor C_1 is charged. The starting point of the charging is shown by a numeral 41 on the time chart in FIG. 4. When the switch S_3 becomes OFF, the capacitor C_2 starts discharging again from a point 42 on the same figure and continues its discharging during the charging period (between points 43 and 44) of the capacitor C_1 after the switch S_1 being turned ON. The discharging of the capacitor C_2 continues until its discharging point reaches a point 45 (corresponding to the above described point 41) where the switch S_3 is again ON after the switch S_1 is turned OFF. The capacitor C_2 will reach the point 45 and is charged by the capacitor C_1 before its discharging is completed. Thus, the terminal voltage of the capacitor C_2 is constantly held larger than the base-emitter voltage V_{BE} of the transistor X_1 and therefore the transistor X_1 is held in a conductive state and the transistor X_2 is non-conductive. Subsequently, in the same manner, the capacitor C_2 continues to charge and discharge by the capacitor C_1 in repetition of the points 41-45.

During the rotation of the commutator 21, the transistor X_1 is held in a conductive state and the transistor X_2 in non-conductive state, and accordingly the relay L_1 and the plunger L_2 respectively are held non-operative.

At the instant when the tape is completely delivered off the supply reel, the reel stops its rotation since the tape end is fixed at the reel hub. As the reel stops its rotation, the reel shaft 11 and also the commutator 21 stop their rotations. The switches S_1 - S_3 being equivalently and substantially formed of the conductor 16 and the brushes 17-19 stop their opening and closing operations.

An instance where the commutator 21 ceases its rotation having the switch S_3 being OFF is now illustrated. As the capacitor C_2 is interrupted from the capacitor C_1 by the switch S_3 being OFF, the capacitor C_2 discharges along an inclination line 51 from a point 50 in FIG. 4. By discharging of the capacitor C_2 the base potential of the transistor X_1 will fall, and after discharging of an amount as predetermined by the capacitor C_2 , the transistor X_1 turns non-conductive, so that the voltage drop of the resistor R_4 will not occur and the collector-emitter voltage V_{CE} of the transistor X_1 becomes larger than the base-emitter voltage V_{BE} . The base potential of the transistor X_2 rises and the transistor X_2 becomes to be in a conductive state.

Further, when the switch S_3 is stopped in the OFF state, the switch S_1 will stop in the state of ON or OFF. Even though the switch S_1 is ON, during discharging of the capacitor C_2 , the capacitor C_1 is charged through the switch S_1 .

As hereinbefore described, if the transistor X_2 becomes to be in a conductive state, the relay L_1 will actuate. By action of the relay L_1 , the switch S_5 is changed in connection from the contact 32a to the contact 32b. The plunger L_2 through the switch S_4 as previously connected to the contact 31b is closed in circuit to the source and it is actuated. The plunger L_2 is in connection to the mechanism of the tape recorder so as to operate the tape recorder in a tape stopping mode or a tape rewinding mode and automatically change over the tape recorder from an ordinary recording and reproducing mode to a stopping or rewinding mode.

The switch S_4 , when the described mode changing mechanism of the tape recorder actuates, mechanically associates with the mechanism and is changed to the contact 31a from the 31b so as to open the circuit to the plunger L_2 . Thereby the plunger L_2 is avoided from a continuous flow of current therein. The capacitor C_2 is closed in circuit for subsequent operation and is charged again.

In case the switch S_3 is ON and the commutator 21 stops its rotation, the switch S_1 stays in the OFF condition. Therefore, the capacitor C_2 discharges and is then charged from the capacitor C_1 through the switch S_3 so that the charged amount of the capacitor C_2 remains along a line 52 for a certain period of time from the point 50 in FIG. 4 and thereafter the charges decrease along a line 54 from a point 53. When the discharging of the electric charges charged in the capacitors C_1 and C_2 nearly come to an end and the terminal voltage of the capacitor C_2 falls below the base-emitter voltage V_{BE} of the transistor X_1 , the transistor X_1 turns non-conductive and the transistor X_2 conductive. As the transistor X_2 is in a conductive state, the relay L_1 actuates in the same manner as described above and the plunger L_2 actuates.

If the rotation of the reel stops as well as the rotation of the commutator 21, the plunger L_2 securely actuates whatever are the states of the opening or closing of the

switches S_1 and S_3 since the switches S_1 and S_3 will not stop in being simultaneously ON.

It is preferred that the discharging period of the capacitor C_2 may be appreciably longer than the opening and closing time of the switches S_1 and S_3 . The diameter of the tape wound on the supply reel is at a maximum at the starting time of tape delivery where the rotation speed of the commutator 21 is slowest and hence the opening or closing time of the switches S_1 and S_3 are longest. Therefore the discharging period of the capacitor C_2 must be determined taking into consideration this longest time. However, it must be determined at a possible minimum time, because if the discharging time of the capacitor C_2 is excessively long, the time from stopping of the commutator 21 to operating of the plunger L_2 will be longer. If the discharging time of the capacitor C_1 is excessively long it will cause a larger time difference (expressed in the interval between the lines 51 and 54 in FIG. 4) in the operation of the plunger L_2 depending on the time of stopping of the switch S_3 in the OFF position and in the ON position. Therefore the discharging time of the capacitor C_1 as described should be preferred also at a minimum. In the embodiment shown, it may be preferably arranged that the time while the plunger L_2 starts its action after the switch S_3 has been stopped in the OFF state is approximately 4 seconds and the time while the plunger L_2 actuates after the switch S_3 has been stopped in the ON state is approximately 8 seconds.

In the following is shown an example of respective resistance values of the resistors R_1 - R_7 and respective capacitance values of the capacitors C_1 - C_5 serving as circuit elements for the circuit of FIG. 3.

Resistance	R_1	3.9K Ω
	R_2	470 Ω
	R_3	68K Ω
	R_4	8.2K Ω
	R_5	2.2K Ω
	R_6	2.2 Ω
	R_7	10K Ω
Capacitance	C_1	47 μ F
	C_2	47 μ F
	C_3	100 μ F
	C_4	0.02 μ F
	C_5	1000 μ F

In the actual circuit a resistor of 10 K Ω in the resistance will be connected to the base of the transistor X_1 .

There will be obtained a more stable operation by use of a temperature-compensating or operation-compensating element for the resistor R_2 .

The invention may, without departing from the spirit thereof, be applied in various modifications other than the above described embodiments. As, for instance, the switches S_1 - S_3 may not exclusively have the construction consisting of the commutator 21 and the brushes 17-19, since those may be substituted for by cam switches cooperating with a cam rotatable with the reel shaft 11. Or a construction may be designed such that by the tape end detection the plunger L_2 is not actuated but a detection and indication device using such means as a lamp to serve for the same object. And the plunger L_2 may be provided to cooperate with other means than the mode changing device. Furthermore, the above described device can be provided not only at the supply reel side but also at the take-up reel side wherein the tape end detection can be applied during the reciprocal movement of the tape.

Even though the tape end is not fixed at the reel, the reel will stop its rotation after all of the tape has been delivered and the detection can be made as desired. Or when the tape is cutoff during the running movement the reel which delivers the tape will stop its rotating so that the same detection can be assured as described above. According to the invention it is likewise possible to make automatically a stopping mode by detection of the tape end even if the tape recorder is locked in a rewinding or a fast forwarding mode. It is noted that in the cassette type tape recorder there is required the above described push button which is to be successively pushed for the rewinding or the fast forwarding mode. According to the present invention, the mode button can be constructed such that it is locked as desired without a need of successively pushing the button.

What we claim is:

1. A tape end detection device for a tape recorder having a shaft and a reel, said device comprising a cylinder of an electrically insulating material secured at one end of the shaft rotatable together with the reel, a conductor having a middle annular portion and first and second protrusions respectively provided laterally on each side of the middle annular portion and being in the same peripheral plane as the middle annular portion, said conductor being provided on the outer peripheral surface of the cylinder, each of said protrusions having a width smaller than the spaces between adjacent protrusions on each side of the middle annular portion, said first and second protrusions on each side of the middle annular portion being in alternate relationship with each other in the transverse direction, three brushes contacting with the middle annular portion and the protrusions respectively, a first brush of said three brushes contacting the first protrusions, a second brush contacting the middle annular portion, and a third brush contacting the second protrusions, a first switch means including the first and the second brushes, the first protrusions and the middle annular portion, a second switch means including the second and third brushes, the second protrusions and the middle annular portion, a power source, a first capacitor connected to the power source through the first switch means, said first capacitor being adapted to be charged intermittently from the power source through the first switch means and to be discharged through the second switch means during rotation of the reel, a second capacitor connected in parallel to the first capacitor through the second switch means, said second capacitor being adapted to be discharged while said first capacitor is intermittently charged through the second switch means, and a detection output means connected to said second capacitor, with said detection output means being adapted to be operated when its terminal voltage falls below a pre-determined voltage by discharging of said second capacitor.
2. The tape end detection device for a tape recorder as defined in claim 1 wherein said detection output means includes a first transistor having a base connected to the second capacitor and to the second switch means and being in a non-conductive state when said second capacitor is discharged through said first transistor and its base voltage falling below a predetermined voltage, a second transistor having a base connected to the output of the first transistor and to the

power source through a resistor, and being in a conductive state by the non-conductive state of said first transistor.

3. The tape end detection device for a tape recorder as defined in claim 2 wherein said detection output means further includes a detection output part connected between the output of the second transistor and the power source, said detection output part having a

relay actuated by conductance of said second transistor and a plunger for changing the mode of the tape recorder, said plunger being actuated by closing of a circuit to the power source by said relay, and change 5 over switch closed at the starting time of the tape recorder and being changed by action of said detection output to open said detection output part.
